UNITED STATES PATENT OFFICE

99,721

DESIGN FOR A FONT OF DISPLAY LETTERS AND FIGURES

Clair McDougal, Saginaw, Mich.

Application July 20, 1935, Serial No. 57,768

Term of patent 14 years

To all whom it may concern:

Be it known that I, Clair McDougal, a citizen of the United States, residing at Saginaw, county of Saginaw, State of Michigan, have invented a new, original, and ornamental Design for a Font of Display Letters and Figures, of which the following is a specification, reference being had to the accompanying drawing, forming part thereof.

The letters consist of square blocks having their diagonals set vertically, arranged in accordance with the pattern shown in the drawing.

I claim:

The ornamental design for a font of display letters and figures, as shown and described.

CLAIR McDUGAL.
